UNITED STATES PATENT OFFICE.

PIERRE COUSIN, OF GRENOBLE, FRANCE.

MACHINE FOR BENDING AND STRETCHING LEATHER FOR THE MANUFACTURE OF BOOTS AND SHOES.

No. 806,113.

Specification of Letters Patent.

Patented Dec. 5, 1905.

Application filed March 3, 1903, Serial No. 146,007.

To all whom it may concern:

Be it known that I, PIERRE COUSIN, a citizen of the French Republic, and a resident of Grenoble, France, have invented a certain 5 new and useful Improved Machine for Bending and Stretching Leather for the Manufacture of Boots and Shoes, of which the following is a specification, such as will enable others skilled in the art to which it appertains 10 to make and use the same.

This invention refers to an improved machine for stretching and bending leather for the manufacture of boots and shoes.

I will now describe my invention with reference to the accompanying drawings, in which—

Figure 1 shows a front elevation of the machine. Fig. 2 shows a sectional elevation on the line A B of Fig. 1. Fig. 3 is a detail elevation of one of the rods *y*, its socket, and ring-nut. Fig. 4 is an elevation of part of the lower portion of the machine. Figs. 5 to 9, inclusive, are detail sectional views showing the different positions of the parts in the operation of stretching the leather.

It will be seen that the machine is supported by four standards *a b c d*, held together by a cross-head *g* and standing on feet *e*, the latter being connected by the angle-bar *f*. Between the respective standards *a b* and *c d* two racks *h* slide in suitable grooves (see Fig. 2) and engage with the pinions *i*, driven by the pinions *k*, fixed on the axle *l*, on the end of which is fixed the fly-wheel *m*. The two racks *h* are connected to the templet *o* by the catch-bolts *p*, by turning which the templet *o* can be disconnected from the said racks. A lower support *q* has two ends which slide in the space between the standards. This support is connected below and near the standards to two racks *r*, which engage with the pinions *s*, fixed on the axle *t*, operated by the fly-wheel *u*. On the same axle *t* is fixed a toothed wheel *v*, with two dogs *w*. The support *q* is provided with four sockets *x*, in which are threaded four screw-threaded rods *y*, having each a groove *y'*, engaged by a screw *y''*, which thus prevents turning of the rods. The rods are raised and lowered by means of the hand-wheels *z* thereon. The rods at their upper ends are provided with jaws *a'*, one fixed to the rod and the other pivoted to the rod, said jaws being adapted to grip between them the ends of the leather, one of the jaws being adapted to be adjusted toward the other to effect the gripping of the

leather by means of adjusting-screws *a''*. Thus the ends of the leather will be held while being operated upon, as presently described.

The cheeks *b'* are placed on each side of the templet *o* and at a distance which may vary. The distance of these cheeks from the templet is regulated by the hand wheels or disks *c'*, which work on screws carried by the said cheeks. The device constituted by the cheeks *b* with the adjusting-screw and support *d'* may oscillate toward the exterior round a pivot *e'*, and the supports *d'* have holes in two places, which engage with soft friction-pins secured on the cheeks *b'*, the object being to keep the cheeks and the templet *o* constantly parallel. The weight of the whole of the support *q* and of the parts carried by it is balanced by the counterweight *f'* and held in suspension by a belt *f''*, passing over a guide-pulley *f'''*, whose shaft is mounted in a standard *b*, the other end of the belt being secured to a disk or other device *f'''*, rigidly connected with the support *q*. The jaws *g'* are invariably upright; but they may be caused to approach or retire symmetrically from the vertical axis of the machine by means of the screws *h'*, each provided on its end with right and left hand screw-threads. These threaded ends engage with threaded portions of the jaws *g'*, the object being that the jaws should approach each other or retire equally and simultaneously at both ends.

The two screws *h'* have each of them a lever-handle *i'*, connected by a rod *k'*, and it is by means of this rod that the distance between the cheeks is regulated. In order that the jaws *g'* should stand absolutely vertical, they are kept in position by the angular pieces *l'* above and by sliding bolts *m'* below, which prevent the supports *d'* from being displaced when the cheeks *b'* are lowered. The supports *d'* are drawn back when the cheeks *b'* have to be lowered.

The operation of the machine is as follows: Let us suppose that the templet *o* is fastened to the toothed bars *h* and that the templet is sufficiently above the cheeks *b'* to allow the necessary space between them for the leather. First, the pieces of leather *x'* are then laid flat on the upper edges of the jaws *g'*. Second, The lower support *q* by means of the fly-wheel *u* and its counterweight *f'* is raised until the upper edge of the movable cheeks *b'* touch the lower edges of the jaws *g'*. The opposing edges of the cheeks *b'* and that of the jaws

g' are now close to one another, and the support *q* is then made immovable by locking the ratchet-wheel *v* by means of pawls *w*. Third, the templet *o* is then lowered by operating the fly-wheel *m*, and consequently the pinions *k l* and the toothed bars *h*. The templet descending folds the leather double and presses it into the space between the cheeks *b'*. If this movement continues, the folds of the leather will be forced against the upper side of the support *q*. Fourth, the ratchet-wheel *v* is then released, and when the toothed bars *h* are further operated the support *q* will be forced to descend under the pressure of the templet *o* until its course is stopped. The support *q* is stopped by bolts *m'*, fastened to the uprights *a b c d*, against which the sides of the support *q* touch. When the dogs *w* are brought into contact with the ratchet-wheel *v*, the support *q* is brought to a standstill. Fifth, if now the back of the piece of leather is free, this part of the leather is folded over, as seen in Fig. 7, and the edges are seized by the corresponding pincers *a'*. Thereupon the hand-wheels *z* are operated in order to stretch the leather forcibly until it covers closely the upper part of the templet. Sixth, when the leather has thus been bent and stretched the templet *o* is released from its toothed bars or racks *r* by the catch-bolts *p*. Then the support *q* is again raised by aid of the fly-wheel *u* until it is in the same position as described above in the beginning of the operation—that is to say, that the upper edges of the cheeks *b'* touch against the lower edges of the jaws *g'*. Thus in order to effect the contact between the upper side of the cheeks *b'* and the lower side of the jaws *g'* it is necessary that the templet *o*, which rises above the cheeks *b'*, should, together with the leather, enter between the upper jaws *g'*. Seventh, the lower support, the templet *o*, and the leather are left in this position. Then the released racks *r* are again raised sufficiently by the fly-wheel *m* above the cheeks *g'* in order that a second templet may be brought into position. Then other pieces of leather are placed against the racks *r* and the second templet is lowered until it comes into contact with the templet and its leather left engaged with the lower part of *g'*. Eighth, then the support *q* is lowered and brought to a standstill by the fly-wheel *u*. The tongs or pincers *a'* are loosened. Then after having withdrawn the bolts *m'* the space between the cheeks *b'* is diminished from the side where the pincers have worked, the said cheeks oscillating on the pivot *e'*, so that the templet, with the leather enwrapping it, may be taken away. The leather is left on the templet to dry. Ninth, the closed cheek *b'* is then again opened, the support *q* is again raised until the cheeks *b'* touch *g'*, and the support is brought to a standstill. Then the second templet, which is left between the

cheeks *g'*, is lowered and the operation continued as described.

What I claim, and desire to secure by Letters Patent, is—

1. The combination with a supporting-frame, of upper cheek-pieces spaced apart as described, lower cheek-pieces also spaced apart, means for raising and lowering the lower cheek-pieces, a templet arranged between the upper and lower cheek-pieces and means for operating the templet. 70

2. The combination with a supporting-frame, of upper cheek-pieces spaced apart as described, lower cheek-pieces also spaced apart, means for raising and lowering the lower cheek-pieces, a templet arranged between the upper and lower cheek-pieces, means for operating the templet, and means for adjusting the lower cheek-pieces toward each other to cause them to firmly grip the 80 leather between them and the templet in the manner set forth. 85

3. In a machine of the character described, the combination with a supporting-frame, of upper cheek-pieces spaced apart as described, 90 lower cheek-pieces also spaced apart, means for raising and lowering the lower cheek-pieces, a templet arranged between the upper and lower cheek-pieces, means for operating the templet, means for adjusting the lower cheek-pieces toward each other to cause them to firmly grip the leather between them and the templet, and means for gripping the leather and stretching the same while confined between the lower cheek-pieces and the templet. 95 100

4. In a machine of the character described, the combination with a supporting-frame, of upper cheek-pieces spaced apart, lower cheek-pieces also spaced apart, one of the lower 105 cheek-pieces being pivotally supported for the purposes specified, means for raising and lowering the lower cheek-pieces, a templet arranged intermediate the upper and lower cheek-pieces and means for operating the 110 templet.

5. In a machine of the character described, the combination with a supporting-frame, of upper cheek-pieces spaced apart, lower cheek-pieces also spaced apart, means for raising 115 and lowering the lower cheek-pieces, a templet arranged intermediate the upper and lower cheek-pieces, means for operating the templet, a support for the lower cheek-pieces, rods adjustably mounted in the said support 120 and adapted to press against the lower cheek-pieces to force them toward each other, and jaws carried by each rod and adapted to cooperate to grip the leather between them in the manner set forth. 125

6. In a machine of the character described, the combination with a supporting-frame, of upper cheek-pieces spaced apart, lower cheek-pieces also spaced apart, means for raising 130 and lowering the lower cheek-pieces, a tem-

plet arranged between the upper and lower cheek-pieces, means for operating the templet, screws h' threaded as described and working in the upper cheek-pieces, the links 5 i' and the connecting-rod k' .

7. The combination with a supporting-frame comprising standards, of racks sliding therebetween, pinions in mesh with the racks, gearing for operating the pinions, a templet 10 detachably connected with the racks, the upper cheek-pieces, the lower cheek-pieces and means for raising and lowering the lower cheek-pieces.

8. The combination with a supporting-frame comprising standards, of upper cheek- 15

pieces supported by the standards, lower cheek-pieces, a support q for the latter cheek-pieces, adapted to slide at its ends between the standards, a counterbalance for the support q , racks, pinions meshing with the racks, 20 gearing for operating the pinions, a templet detachably connected with the racks, all arranged as and for the purpose specified.

In testimony that I claim the foregoing I have hereunto set my hand this 16th day of 25 February, 1903.

P. COUSIN.
